Attorneys

UNITED STATES PATENT OFFICE.

FRANK HENRY, OF LOS ANGELES, CALIFORNIA.

MONOLITHIC FLOOR.

Application filed January 11, 1923. Serial No. 611,965.

To all whom it may concern:

Be it known that I, FRANK HENRY, a citizen of the United States, residing at Los Angeles, in the county of Los Angeles and State of California, have invented new and useful Improvements in Monolithic Floors, of which the following is a specification.

My present invention relates to a method of making monolithic floors showing designs upon their surfaces, and to means for the production of such floors, or equivalent surfaces; and it is an important object of my invention to provide simple and effective means and a method whereby an imitation of tile or a like effect may be produced.

It is a further object of my invention to provide a floor of the character referred to which will wear uniformly, the material constituting the "tiles," and the material employed in forming the "joints" therebetween being of substantially the same wearing qualities, although different in color.

It is a further object of my invention to provide an easy method for securing uniformity in the width of the joint lines between the respective tiles, throughout a given piece of work, and to expedite the production of a tile effect, my means and method being such as to require comparatively little skill.

It is a further object of my invention to provide easy means for bringing the top of a floor formed of plastic material to exactly the final level desired, the material which is to constitute the "joints" between the "tiles" being preferably preformed and applied as a grid to any suitable foundation, preferably a foundation of plastic material, such as concrete.

It is a further object of my invention to provide means whereby the diameter of the joints as compared with the diameter of the tiles may be conveniently varied, a grid of plastic material having substantially the same wearing qualities as the material of which the tiles are to be formed being preferably cast in advance, and permitted to harden before being laid upon a suitable foundation.

A further object of my invention is to provide means whereby the details of any desired geometrical or other configuration may be worked out in advance, and a suitable grid made in conformity with the

design adopted, it being then only necessary to assemble the grids in their desired relationship and to fill in the interstices thereof with plastic materials of the respective colors desired.

It is a further object of my invention to provide grids of the general character indicated, which shall be adapted to extend into and bond with a foundation material, and which shall also form a satisfactory and permanent bond with the plastic materials subsequently disposed in the mentioned interstices, so that a monolithic effect is produced, even though the surface of the floor exhibits a design, such as may ordinarily be produced by the use of tile or mosaic material.

It is a further object of my invention to provide a monolithic structure in which the tendency to fracture may be reduced to a minimum, but in which, in case of fracture, the lines along which cracks may occur shall be predetermined.

It is a further object of my invention to facilitate the reinforcing of floors having a design or tile effect.

It is a further object of my invention to provide joint grids or units formed of plastic material and so hardened, in advance, as to permit of being transported and otherwise treated as articles of commerce, without serious liability to breakage or deterioration.

Other objects of my invention will appear from the following description and the appended claim, it being understood that certain parts or features of my invention may be independently used, and that various modifications may be made therein without departing from the spirit and scope of my invention as the same is indicated in the mentioned description and claim.

It is believed that my invention will be readily understood from the following description of one specific embodiment thereof, taken in conjunction with the accompanying drawings, in which—

Figure 1 is a perspective view showing a grid, preformed in accordance with my invention, and partially embedded within the foundation of plastic material, in readiness for the introduction of suitably colored plastic materials into the interstices shown.

Fig. 2 is a plan view of one entire grid, adapted to be assembled with like grids in the production of a floor presenting the ap-

pearance of a floor formed with hexagonal tiles.

Figs. 3, 4 and 5 are vertical sections, being detail views intended to show specific types of reinforcement.

Referring, in further detail, to the specific embodiment shown, 1 is a grid, which may be provided with reinforcement in the form of wires 2, and may be so embedded in a concrete foundation 3 as to establish a true level at the top of said grids. The interstices 4 may be then filled with a plastic composition which may be terrazzo or may be of any uniform color desired, preferably a color contrasting with the materials employed in the production of the grid.

It will be understood that the procedure indicated may obviate the necessity for bringing the concrete foundation to an exact level, the grids being adapted to be embedded to varying depths in the concrete foundation, while the latter is sufficiently soft to bond therewith, an elevation in the concrete foundation being indicated at E and depressions being indicated at D and D'. It will also be understood that the grids ought to be formed sufficiently in advance of the time they are to be used to enable the cementitious or other material of which they may be formed to acquire hardness and strength. I prefer to form the grids in the representation of a considerable number of units, and I find it advantageous to complete all of the units at the margins of the respective grids. This contributes to their strength and minimizes the liability to breakage, although it may also necessitate a cutting or sawing of the outside elements when a plurality of grids are assembled in the formation of a floor.

Any suitable mode of reinforcement may be employed. It would obviously be possible, for example, to employ straight wires in the formation of a grid having rectangular openings. For the formation of a grid such as is shown in Fig. 2, various expedients may be employed, such as the employment of a mesh resembling "chicken wire," and reinforcement of this character may be introduced near the top and again near the bottom of the grid elements as indicated in Fig. 3. Alternatively, a reinforcement suitable to the production of hexagonal openings may be made by the assembling of hex-

agonal units of sheet material, and these may be secured together in any suitable way, as by spot welding in proximity to the points of juncture. As shown in Fig. 4, a reinforcement of the character last referred to may be so modified as to serve as a bottom element of the mold in which the grids may be cast. It would appear possible, also, to employ expanded metal suitably formed and inserted in the manner suggested in Fig. 5.

Depending upon the size of the room and the taste of the architect or owner, the diameter of the joint lines between the respective elements of an ultimate design may be made comparatively wide, or comparatively narrow; and to this end, I find it advantageous to give a slight taper to the vertical sections of the grid elements. The grid elements may then be employed with the wide side up when a wide joint line is desired, or inverted when a narrow joint line is desired, the respective effects here referred to being illustrated in Figs. 4 and 5. It will be obvious that the mentioned taper in the grid elements will also facilitate the separation of the grids from the forms in which they may be cast, any suitable mode and means of casting being employed; and it will be obvious that after the grids are suitably assembled and leveled upon a foundation prepared therefor, it is only necessary to fill the respective interstices with the desired composition or compositions and strike off the excess material to the level of the top of the grids, smoothing the surface down and permitting the whole to become consolidated into a unitary or monolithic structure.

Any suitable plastic composition may be employed, but, as indicated above, it is desirable that the composition used for the grids should so closely resemble that used in the interstices thereof that, irrespective of the design effect produced, the wearing qualities of the floor should be uniform.

What is claimed is:

A monolithic product comprising a grid preformed of plastic material, and a plastic filling within the interstices of said grid, said grid being provided with reinforcing elements embedded therein.

In testimony whereof I have signed my name to this specification.

FRANK HENRY.
